POURING SPOUT AND CLOSURE

Carl McQuinn, Decatur, Ill., assignor to Williams Sealing Corporation, Decatur, Ill., a corporation of Illinois

Application March 11, 1938, Serial No. 195,405

11 Claims.

(Cl. 221—5)

The present invention relates to closures for containers of the type having pouring spouts associated therewith. More particularly, the invention is concerned with a cap for a dispensing can spout having a non-circular pouring opening. Also, the invention includes a novel form of spout having an oval pouring opening, providing a laterally projecting pouring lip.

It is an object of the invention to provide an improved cap for sealing and re-sealing the opening of such a spout. The cap not only forms an efficient original seal, but is constructed so as to constitute an improved means for re-sealing the receptacle, after it has once been opened.

15 The primary objects of the invention, therefore, are to provide an improved pouring spout and a cap which may be applied to the pouring opening of such a spout and locked thereon, to provide a substantially hermetic seal.

20 In the past, difficulties have been encountered in providing efficient seals for oval-shaped pouring spouts, for the reason that the pointed end of the spout, normally used as a pouring lip, could not be brought into tight sealing engagement with 25 the cap. In certain prior art constructions, means, such as screw threads, were provided to draw the cap downwardly on the spout, but, because of the oval shape of the spout, the threads were interrupted at the pouring lip. In such constructions, nothing was provided at the end of the pouring lip to draw the cap downwardly into tight sealing relation therewith, and an inefficient seal resulted.

It is an object of the present invention to provide means positioned directly at the tip of the pouring lip to secure the cap in sealing relation to the spout at that point. Further, tensioning means are provided at the opposite end of the cap, to draw the cap down onto the spout to make a 40 tight seal at that end, as well as at all other points around the margin of the spout.

In the accompanying drawing, an illustrative embodiment of the present invention is shown, but it must be understood that the invention is 45 not limited to the details of construction specifically shown therein and described below.

In the drawing:

Figure 1 is a side elevation of the cap applied to the spout of a receptacle.

50 Figure 2 is a rear elevation similar to Figure 1.

Figure 3 is a top plan view.

Figure 4 is a vertical longitudinal section through the cap and spout.

Figure 5 is a bottom plan view of the cap with 55 the locking lever removed.

Figure 6 is a perspective view of a preferred form of locking lever.

Figure 7 is a bottom plan view of a novel form of spout member.

Figure 8 shows one manner of applying the cap 5 to a spout.

Figure 9 shows another method, with the cap and spout constructed with slightly different relative dimensions.

Figure 10 is a cross-sectional detail taken on 10 line 10—10 of Figure 7.

The cap, preferably made of sheet metal, comprises a flat top 10, which is oval in plan, as shown in Figures 3 and 5. A marginal flange 11 projects downwardly from the top and is jointed 15 thereto by an upwardly projecting, rounded, marginal reinforcing rib 12 which preferably extends entirely around the perimeter of the top. At the pointed, forward end 13 of the cap, the skirt 11 terminates at its lower end in an inwardly and 20 downwardly inclined portion 14. This web-like member 14 is integral with the skirt and is disposed to span the pointed end of the oval as shown in Figure 5. As explained below, the web 14 plays an important part in securing the cap on 25 the receptacle and, more particularly, in securing the forward, pointed end of the cap onto the pouring lip of the spout, in a tight, wedging relation, providing a hermetic seal at that end.

At the rear end 15 of the oval, the skirt 11 is 30 extended rearwardly to provide spaced ears 16, 17. The ears are provided with apertures 18 which receive laterally projecting trunnions 19 on a locking lever 20. The locking lever is preferably made from sheet metal by a stamping operation. 35 It comprises an operating handle portion 21, a rounded cam shoulder 22 and a flat, terminal, locking portion 23. Obviously, the lever is mounted in the apertures of the ears 16, 17 for pivoting movement with respect to the cap. The rear ends 40 of the ears 16, 17 are bent inwardly to engage the lever with a spring action to hold the same in upright position, as shown in dotted lines in Figure 8, during the initial step in the application of the cap to the spout.

45 The cap is provided with a conventional, resilient sealing pad 24 which is of the same oval shape as the spout and the top of the cap.

The spout preferably used with the cap of the present invention is similar to the spout shown 50 in my prior application Serial No. 132,436, filed March 22, 1937. However, it has been modified and improved to cooperate with the cap of the present invention in a new and efficient manner.

The spout comprises a cylindrical neck 25 55

adapted to be secured at its lower end to the top of a can by any approved joint. The neck is provided with a reinforcing rib 26 intermediate its ends. Above the rib, there is a laterally projected portion 27 forming a pouring lip. The projecting portion merges with the upper end of the neck to provide an oval pouring opening, surrounded by a down-turned marginal flange or a semi-circular bead 28. This bead provides a rounded sealing surface 29 of substantial width entirely around the opening. At the pouring lip portion 27, the flange 28 terminates at its lower end in a raw edge spaced from the neck 25 and the undersurface of the projecting portion 27, thereby providing a dripless pouring lip.

At the rear, wider or blunt end 15 of the spout, the flange 28 is provided with an extension 30 which is curled up to form a substantially circular or tubular bead at that point, constituting a bearing surface for the cam surfaces 22, 23 of the locking lever 20.

The skirt 11 of the cap preferably is of a size to embrace closely the outer edge of the down-turned flange 28 of the spout, substantially entirely around the perimeter thereof. The portion 14 of the cap skirt serves as a hook, to underlie the flange 28 of the spout at the tip or pointed end thereof. As shown in Figure 8, the cap is preferably applied to the spout by hooking the web 14 under the lower edge of the flange 28 at the point of the spout. The hooking action results in a preliminary compression of the pad 24 at the point of the oval. The rear of the cap is then swung downwardly about the point 31 as a fulcrum, thereby tightly compressing the sealing pad 24 at the front end. The cam shoulder 22 of the locking lever is disposed under the bead 30, and when the lever is depressed, the rear end of the cap is drawn downwardly by a camming action, the force being directed on a downwardly and rearwardly inclined line, to pull the rear end of the cap downwardly into sealing engagement with the spout, with great force. When the lever 20 is moved still further downwardly, the flat portion 23 of the head of the lever comes into engagement with the bead 30 and the cap is locked in position. The relation between the head of the lever and the bead on the spout is such that the cap can be drawn downwardly increasing amounts, to compensate for the compression of the gasket, which inevitably results when the receptacle is repeatedly re-sealed.

In Figure 9, a modified method of applying the cap is disclosed, which may be employed whenever the circumference of the cap skirt exceeds the circumference of the down-turned flange on the spout by any substantial degree. The cap is placed on the spout with the down-turned flange 28 of the spout positioned at an intermediate point in the web 14. The locking lever 20 may then be used to draw the rear end of the cap rearwardly and downwardly, as previously described. This action results in a wedging movement between the flange 28 and the web 14, thereby drawing the forward end of the cap downwardly upon the spout at the pouring lip, to provide a tight seal.

If desired, the ears 16, 17, which carry the locking lever, may press inwardly against the lever with a spring tension to hold the same with a snap action in an upwardly disposed position or in a downwardly disposed, locked position.

It should be noted that the web portion 14 at the pointed end of the cap is of substantial length equal, in the preferred embodiment, to at least

one-third of the width of the cap top at its widest point. This feature lends strength and rigidity to the cap and prevents transverse bowing of the top under the influence of sealing tension. Also, the ears 16 and 17 are spaced apart a distance substantially equal to the length of the web 14, so that the sealing tension applied to the cap by the lever is applied at two well spaced points. These features, in combination, result in a more substantial, rugged construction and in an improved distribution of the sealing forces.

The upstanding rib 12 around the margin of the top reinforces and stiffens the flat cap top and prevents longitudinal bowing of the same, under the influence of the sealing tension applied to the ends of the cap. As a result, the plane flat surface of the top is maintained, and the sealing gasket 24 is evenly compressed upon the upper surface of the bead 28 to provide a uniformly tight seal entirely around the opening of 20 the spout.

The depending marginal flange 11 also assists in stiffening and reinforcing the flat, cap top. It cooperates with the up-standing rib 12 to prevent longitudinal bowing of the top. This cooperation of the flange and rib results in the provision of a remarkably stiff, rigid cap top which, although positively secured to the spout only at its ends, provides an hermetic seal by compressing the gasket 24 uniformly between the top and 30 the spout, entirely around the perimeter of the latter.

It must be understood that the invention is not limited to the details of construction shown and described herein, but covers all modifications coming within the scope of the appended claims or their equivalents.

I claim:

1. A closure for a spout having an oval pouring opening, said closure comprising an oval top, a depending marginal skirt extending continuously around the forward pointed end and the sides of the oval and terminating at the rear blunt end in spaced rearwardly projecting ears, the skirt at the pointed end terminating downwardly in a rigid web projecting inwardly beyond the point of the oval, adapted to hook under the pouring lip of the spout, the lower edge of the web and of the remainder of the skirt being continuous and merging into each other, and a locking lever pivoted to said ears and having a portion directly engaging the spout at the rear blunt end thereof, to draw the closure downwardly on the spout about said web as a fulcrum.

2. A closure for a spout having an oval pouring opening, said closure comprising an oval top, a depending marginal skirt extending continuously around the forward pointed end and the sides of the oval and terminating at the rear blunt end in spaced rearwardly projecting ears, the skirt at the pointed end having at its lower end a rigid inwardly projecting web terminating in a free edge spaced inwardly from the point of the oval, adapted to hook under the pouring lip of the spout, the lower edge of the skirt and the free edge of said web being substantially continuous and merging into each other, and a locking lever pivoted to said ears and having a portion directly engaging the spout at the rear blunt end thereof, to draw the closure downwardly on the spout about said web as a fulcrum.

3. A closure adapted to form a top seal and to close the upper end of a spout having an oval opening, said closure comprising a flat top having an oval shape similar to the shape of the

spout opening and a depending marginal skirt extending continuously from spaced points at the rear blunt end of the oval around the sides and the forward pointed end thereof, the skirt between said spaced points being interrupted and being extended outwardly to provide a pair of rearwardly projecting ears, the lower edge of the skirt being continuous and unbroken and being projected inwardly to form a hooked portion at the pointed end of the oval, adapted to be disposed under the edge of the spout at the sharp end thereof, and a lever pivoted to said ears and having an end adapted to engage directly the spout and draw the cap downwardly about the hooked portion as a fulcrum to bring said flat top into sealing engagement with the spout.

4. In combination, a sheet metal spout for a receptacle and a closure therefor, said spout having a laterally projecting enlargement forming a pouring lip and a down-turned flange around its perimeter forming a substantially semi-circular bead in cross-section and providing a substantially dripless edge at the pouring lip, the upper surface of said bead being disposed in a single plane, said flange at the end of the spout opposite the pouring lip being provided with an extension curled up to form a substantially circular bead portion, said cap comprising a top, a depending skirt having a hooked portion underlying said pouring lip and a lever pivoted to the opposite end thereof adapted to engage under the circular bead portion on the spout as a bearing, to draw the cap downwardly upon the spout.

5. An oval cap for use with a pouring spout having an oval opening, said cap comprising a flat top having an upwardly projecting marginal reinforcing rib around its perimeter, a marginal skirt depending from the outer edge of said rib and extending continuously from spaced points adjacent the rear blunt end of the oval around the sides and the front pointed end thereof, the skirt having a continuous, unbroken lower edge and a rigid portion at the pointed end projected inwardly to hook under the pointed end of the spout, and a lever pivoted to the opposite end of the cap skirt adjacent said spaced points for drawing the same downwardly upon the spout, said reinforcing rib and the depending skirt comprising means for preventing longitudinal bowing of said flat top under the influence of the downward pull of the lever.

6. A closure for a spout having an oval pouring opening, said closure comprising an oval top, a depending marginal skirt extending continuously around the forward pointed end and the sides of the oval and terminating at the rear blunt end in spaced rearwardly projecting ears, the skirt at the pointed end terminating downwardly in a rigid web having a free edge projecting inwardly beyond the point of the oval, adapted to hook under the pouring lip of the spout, the free edge of the web and the lower edge of the remainder of the skirt being substantially continuous and merging into each other, and a locking lever pivoted to said ears and having a portion directly engaging the spout at the rear blunt end thereof to draw the closure downwardly on the spout about said web as a fulcrum, said web and the space between the ears to which the lever is pivoted being substantially equal to each other and equal to substantially one-third of the maximum width of the cap top.

7. The combination with a receptacle having a neck terminating in a pouring opening and an outwardly projecting bead surrounding said opening, of a closure cap comprising a substantially flat top, a depending marginal skirt having a hook portion shaped to underlie said bead, and a locking lever carried by said skirt diametrically opposite said hook portion, said lever comprising an operating handle, and a rounded cam shoulder terminating in a flat locking portion, said shoulder being shaped and positioned to engage under said bead with a camming action to draw the cap downwardly upon movement of the lever, said flat portion being engageable with the bead to lock the cap on the receptacle.

8. The combination with a receptacle having a neck terminating in a pouring opening and having an outwardly projecting bead surrounding said opening, of a closure cap comprising a top, a depending marginal skirt having a hook portion at one end shaped to underlie said bead and, at the other end, a pair of spaced ears projecting rearwardly, and a locking lever carried by said ears, said lever comprising a rounded cam shoulder terminating in a flat portion, said shoulder being shaped and positioned to engage under said bead with a camming action to draw the cap downwardly upon movement of the lever, said flat portion being engageable with the bead to lock the cap on the receptacle.

9. In combination, a receptacle having a neck terminating in an oval pouring opening and having a down-turned flange surrounding said opening and forming a partial bead, the material of the flange at the rear, widened end of the oval being elongated and curled under to provide a bearing surface, and a closure cap for the opening comprising a top, a depending marginal skirt having a hook portion shaped to underlie said partial bead at the forward, pointed end of the oval, and a locking lever carried by said skirt at the rear wider end of the oval, said lever comprising a rounded cam shoulder and a flat locking portion, said shoulder being shaped and positioned to engage under said bearing surface with a camming action to draw the cap downwardly upon movement of the lever, said flat portion being engageable with the bearing surface, to lock the cap on the receptacle.

10. A closure cap comprising a substantially flat top, a depending marginal skirt provided with rearwardly projecting spaced, perforated ears, and a sheet metal locking lever having laterally projecting trunnions pivotally mounted in the perforations in said ears, said lever comprising an operating handle projecting rearwardly from said trunnions, a rounded cam shoulder inwardly of the trunnions and a plane, terminal portion merging with said shoulder.

11. A cap for use with a spout having an oval opening, said cap comprising an oval-shaped top, a depending marginal flange having an inwardly projecting lower edge at the pointed end of the oval and a pair of rearwardly projecting, spaced, perforated ears at the rear end of the oval, and a locking lever comprising a sheet metal stamping having outwardly projecting trunnions pivoted in the perforations in said ears, said lever comprising a rounded cam shoulder terminating in a locking portion.

CARL McQUINN.
